UNITED STATES PATENT OFFICE.

WILLIAM F. TROAST, OF LANCASTER, PENNSYLVANIA.

DESIGN FOR A VEHICLE-TIRE.

59,794.

Specification for Design.

Patented Nov. 22, 1921.

Application filed December 14, 1920. Serial No. 430,758. Term of patent 7 years.

To all whom it may concern:

Be it known that I, WILLIAM F. TROAST, a citizen of the United States, residing at Lancaster, in the county of Lancaster and State of Pennsylvania, have invented a new, original, and ornamental Design for Vehicle-Tires, of which the following is a specification, reference being had to the accompanying drawing, forming part thereof.

Figure 1 is a perspective view, and Fig. 2 a top plan view of the new design.

I claim:—

The ornamental design for a vehicle tire as shown.

WILLIAM F. TROAST.
